UNITED STATES PATENT OFFICE.

WALTER KANE, OF SARNIA, ONTARIO, CANADA.

CAR-DOOR FASTENER.

Application filed July 25, 1922. Serial No. 577,484.

To all whom it may concern:

Be it known that I, WALTER KANE, a subject of the King of Great Britain, and a resident of Sarnia, in the Province of Ontario and Dominion of Canada, have invented certain new and useful Improvements in Car-Door Fasteners, of which the following is a specification.

This invention relates to an improvement in car door fasteners of the type forming the subject-matter of my prior Patent No. 1,361,868.

The object of the invention is to provide a device of this character which is easily operable to secure or release the door in either fully closed or partly open position and which is adapted to secure the door in closed position or in partly closed position as desired in such manner as to admit of ventilation of the car.

Another object is to provide a device of this character which is of extremely simple and durable construction, reliable in operation and easy and inexpensive to manufacture and apply.

Other objects and advantages of the invention reside in certain novel features of the construction, combination and arrangement of parts which will be hereinafter more fully described and particularly pointed out in the appended claims, reference being had to the accompanying drawings forming part of this specification and in which:

Figure 1 is a view in side elevation, illustrating the invention applied to a car door;

Figure 2 is a view in section on line 2—2 of Figure 1;

Figure 3 is a detail perspective view of the locking bar and its angle brackets;

Figure 4 is a detail perspective view of the sealing chain;

Figure 5 is a view in side elevation, showing another embodiment of the invention;

Figure 6 is a view, taken approximately on line 6—6, of Figure 5, showing the locking bar in locking position and the sealing chain positioned to seal the car;

Figure 7 is a detail perspective view of the locking bar and angle brackets of the form of the invention shown in Figures 5 and 6; and

Figure 8 is a fragmentary perspective view, illustrating a slightly modified means for sealing the locking bar.

Referring to the drawings, it will be seen that in all embodiments of the invention

there is contemplated a car which is a box car or the like, which is designated at C and which is provided with a door D suspended or supported in any suitable manner.

In the embodiment of my invention shown in Figures 1 to 4, inclusive, the numeral 10 designates a locking frame suitably secured to the car door and having arms 11, the lower ends of which project beyond the lower edge of the car door and are inwardly curved and tapered, as at 12.

Spaced angle brackets 13 are secured to the portion of the car underlying the door. A locking bar 14 is provided and has its ends inturned, as at 15, and pivotally secured as at 16, to the angle brackets 13. In this form of the invention the arrangement is such that the arms 11 are spaced apart such a distance that they are adapted to engage the inturned ends 15 of the locking bar when the locking bar is in locking position. It is obvious that when the locking bar 14 is turned up to horizontal position, as shown in Figures 1, 2 and 3, it occupies a locking position since it engages the locking arms 11 and prevents the door from being swung outwardly. The engagement of the arms 11 with the inturned ends 15 prevent longitudinal movement of the door D.

A sealing chain 17 has one end secured, as at 18, to the car door and is provided at its opposite end with a hook 19. This sealing chain is adapted to be extended around the locking bar, as shown in Figure 2, the hook 19 being then engaged with one of the links of the chain adjacent the connection 13. With the chain so positioned the locking bar is held in locking position and the car may be conveniently sealed by applying a seal 20 to the sealing chain 17.

In the embodiment shown in Figures 5 to 7, the locking frame is designated at 25, and as in the other embodiments of the invention includes locking arms 26 projecting down beyond the car door as before.

Spaced angle brackets, designated at 27, are carried by the car below the car door but the angle brackets 27 are spaced apart a distance substantially greater than the distance between the locking arms 26, this arrangement permitting of the door being secured in closed position or in partly open position, as desired. A locking bar, designated generally at 28 is provided and has its ends inturned, as at 29, and pivotally secured, as at 30 to the angle brackets 27. The

body of the locking bar 28 is provided with a number of offsets of U-shaped formation defining seats or keepers 31. Any number of such seats or keepers 31 may be provided and for the sake of illustration two sets are shown. It will be understood that there are two keepers in each set one for each of the locking bars 26. One set of keepers when cooperable with the locking arms functions to hold the door in closed position and the other set permits of holding the keepers in partly open position.

A sealing chain 32 has one end secured to the car door by a connection 33 and has its opposite end provided with a hook 34. The sealing chain is extended around the locking bar and then has its hook interengaged with one of the links of the chain. The seats or keepers 31 admit of the locking of the door in such manner as to provide for ventilation as may be seen in Figure 6 since the door is canted or inclined slightly outwardly when in locked position. A seal 35 is applied to the sealing chain 32 as in the previous embodiments.

In both embodiments of the invention a safety chain 40 is provided and has one end secured, as at 41, to the car door and has its opposite end slidably connected to a safety bar 42 provided on the car. In the open or unlocked position of the door this safety chain and safety bar prevent the door being blown out so far as to be dangerous.

In Figure 8 there is shown a slightly modified means for sealing the lock. In this Figure the numeral 45 designates a lock bar shown for the sake of illustration as similar to that shown in Figures 5, 6 and 7. The lock bar of course is adapted to coact with the locking frame carried by the car door. The numeral 46 designates one of the spaced brackets upon which the bar 45 is pivotally supported. The locking bar 45 is provided with an opening 47 in its inturned end and the adjacent portion of the bracket 46 is also

provided with an opening designated at 48 and adapted to come into registry with the opening 47 when the locking bar 45 is in locked position. The sealing hook 49 will then be inserted through the opening, and to this sealing hook the seal 50 is applied.

I claim:

1. In a lock for car doors, a locking frame adapted to be secured upon the car door and having locking arms projecting beyond the same, spaced angle brackets secured to the car, a locking bar pivotally mounted upon the angle brackets and having a plurality of offsets therein defining keepers cooperable with the locking arms of the frame, and means for sealing the locking bar in locked position.

2. In a lock for car doors, a locking frame adapted to be secured upon the car door and having locking arms projecting beyond the same, spaced angle brackets secured to the car, a locking bar pivotally mounted upon the angle brackets and having a plurality of offsets therein defining keepers cooperable with the locking arms of the frame.

3. In a lock for car doors, locking arms adapted to be secured to the car door to project beyond the same, the locking arms having their lower ends curved inwardly and tapered, spaced angle brackets secured to the car, and a locking bar pivotally mounted upon the angle brackets and cooperable with the locking arms.

4. In a lock for car doors, a locking frame adapted to be secured to the car door and having locking arms projecting down below the same, spaced angle brackets adapted to be secured to the car, a locking bar having inturned ends pivotally secured to said angle brackets, the locking arms of the frame being engageable with said inturned ends in the locked position of the door, and sealing means for sealing the locking bar in locked position.

WALTER KANE.
